(57) **CLAIM**

The ornamental design for a belt hook, as shown and described.

DESCRIPTION

FIG. 1 is a perspective view of the belt hook.

FIG. 2 is a front elevational view of the belt hook of FIG. 1. FIG. 3 is a rear elevational view of the belt hook of FIG. 1. FIG. 4 is a side elevational view of the belt hook of FIG. 1, the opposite side being a mirror image thereof.

FIG. 5 is a top plan view of the belt hook of FIG. 1.

FIG. 6 is a bottom plan view of the belt hook of FIG. 1.

FIG. 7 is a perspective view of a variant of the belt hook. FIG. 8 is a front elevational view of the belt hook of FIG. 7. FIG. 9 is a rear elevational view of the belt hook of FIG. 7. FIG. 10 is a side elevational view of the belt hook of FIG. 7, the opposite side being a mirror image thereof.

FIG. 11 is a top plan view of the belt hook of FIG. 7; and, FIG. 12 is a bottom plan view of the belt hook of FIG. 7.
